UNITED STATES PATENT OFFICE.

GEORGE C. BRUHN, JR., OF ELM GROVE, WEST VIRGINIA, ASSIGNOR OF ONE-HALF TO
WILLIAM F. BRUHN, OF WHEELING, WEST VIRGINIA.

PHOTOGRAPHIC-PLATE MAGAZINE.

1,166,353.

Specification of Letters Patent. Patented Dec. 28, 1915.

Application filed June 16, 1915. Serial No. 34,342.

To all whom it may concern:

Be it known that I, GEORGE C. BRUHN, Jr., a citizen of the United States of America, and resident of Elm Grove, county of Ohio, and State of West Virginia, have invented certain new and useful Improvements in Photographic-Plate Magazines, of which the following is a specification.

This invention relates broadly to photographic apparatus, and specifically to a magazine for photographic plates.

The primary object of the invention is to provide a magazine in which may be carried in small compass a relatively large number of the ordinary sensitized plates employed in photographic cameras.

A further object is to provide a magazine in which plates are carried separate and apart from individual plate holders and which is adapted to receive such plates from and to deliver plates to a plate holder without exposing them to the light.

A still further object is to provide a device of the character mentioned to and from which plates can only be delivered when an individual plate-holder is associated therewith; and, further, to provide an apparatus which is convenient to operate.

With these and various other important objects in view, the invention resides in the features of construction, arrangement of parts and combinations of elements which will hereinafter be exemplified, reference being had to the accompanying drawings, forming a part of this specification, in which—

Figure 1 is a front elevation of the magazine, showing a plate holder associated therewith in plate-introducing position; Fig. 2 is a side elevation of the same; Fig. 3 is an enlarged view of the magazine partially in top plan and partially in horizontal section; Fig. 4 is a view of the same partially in central vertical section and partially in end elevation, the cover-plate for the indicator-disk and a portion of the actuating-gear for the carriage being shown removed; Fig. 5 is an inner face view of a portion of said carriage-actuating gear, removed; Fig. 6 is an outer face view of the same, partly in broken section; Fig. 7 is a horizontal section of the same; Fig. 8 is a view of the individual plate holder, partially in side elevation and partially in broken section; Fig. 9 is a longitudinal sec-

tion of the same; Fig. 10 is an end elevation of a broken portion of the lower end of the individual plate holder, showing the cam; Fig. 11 is an edge view of the same; and—Fig. 12 is an enlarged partial longitudinal section and a partial broken elevation of the magazine and individual plate holder, the latter being shown mounted in plate introducing position.

Referring to said drawings in which like designating characters distinguish like parts throughout the several views—1 indicates the opposite side-walls, 2 the end-walls, and 3 the bottom of a rectangular magazine casing the interior depth and width of which substantially correspond to the length and width of the photographic plates which it is desired to carry, while its thickness may be varied to give it any desired plate-carrying capacity. The opposite vertical end walls 2 of said casing carry on their inner faces spaced vertically-disposed strips 4, preferably of thin sheet metal, which project slightly inward into the interior to form therebetween oppositely disposed pockets adapted for receiving sensitized glass photographic plates in spaced non-contacting relation.

The upper end or top of the casing is closed by a flexible curtain 5 of a suitable light-excluding material, said curtain being stretched across said top and movable over rollers 6 provided at the upper ends of the opposite sides 1. The opposite ends of said curtain are movable in open spaces 7 formed between said sides 1 and an outer sheath or covering 8 of metal or other suitable material, the upper portions of said sides being offset and made of less thickness than the lower portions thereof to provide said spaces 7, as is most clearly shown in Fig. 4. A pair of flexible straps or tapes 9 have their opposite ends attached to the opposite ends of said curtain at points adjacent to the lateral edges of the latter, said tapes being passed downward to and under suitable small rollers 10 mounted at opposite ends of suitable horizontal grooves or channels 11 provided in the end walls 2, said tapes thence crossing from one side to the other through said channels, as shown in Figs. 3, 4 and 5.

At the top of the casing each of the lateral edges of the curtain 5 travels back and forth beneath a narrow horizontally dis-

posed metallic strip 12 which extends from one side-wall 1 to the other and which is rigidly attached to the adjacent end wall 2. Said strips 12 not only serve to prevent light from passing by the edges of the curtain into the interior of the casing, but also as seats for the opposite ends of a movable carriage which is herein generally designated by the numeral 13. Said carriage is substantially rectangular in cross section and comprises a pair of oppositely disposed side plates 14 and end portions 15, the latter having secured thereto, preferably by brazing, interiorly threaded eye-pieces 16 through which are threaded screws 17 having micrometer threads, said carriage being thus adapted for adjustment to any desired position on the top of the casing by turning of said screws 17. Located within the confines of the carriage 13 and rigidly attached to the curtain 5 are two oppositely disposed longitudinal strips 18 of wood or other suitable material which are so spaced apart as to afford therebetween a longitudinal slot or opening 19 of sufficient width to permit of the passage therethrough of a glass photographic plate of the usual thickness. Said opening 19 registers with a slot 20 provided in the curtain for admitting of the passage of such photographic plate. Secured to the inner faces of the side-plates 14 of the carriage above said strips 18 and at a spaced distance below the open top of the carriage are the opposite lateral edges of a horizontally disposed longitudinal metal plate 21 having a slot 22 therein which is disposed in vertical alignment with the slot 20 in the curtain; and secured on the under side of said plate 21 is a metal member 23 of inverted trough shape having a slot 24 therein registering with said slot 22. Pivotaly mounted to swing into and out of seating relation to the under side of the member or trough 23 is a shutter 25 which is designed to close the passages constituted by the registering slots 22 and 24 for excluding light from the interior of the casing and which is normally maintained in its seated position, as by one or more suitably arranged springs 26.

Suitably attached to the upper face of the plate 21 and surrounding the slot 22 of the latter is one or more layers 27 of felt or like material designed to constitute a seat 55 for the lower edge of an individual plate holder which is herein designated by the numeral 28 and which is designed both as a means for introducing sensitized glass plates in a camera and as a means for introducing such plates into and receiving such plates from the interior of the casing 1 without at any time permitting such plates to come into contact with light. Said plate holder comprises a rectangular frame 29 of 60 a character similar to that employed in or-

dinary plate holders, a back 30, a plate-receiving pocket 31, the latter being located between said back 30 and the ordinary dark slide 32 which is slidable into and out of the usual slide-grooves of the frame in the usual manner. Secured to the lower end of the frame 29 is a metal box 33 which is of substantially U-shape in cross-section and having closed ends, the outer dimensions of said box being such that it may be fitted 75 neatly within the open top of the carriage 13. A longitudinal slot 34 is provided in the bottom of said box 33 through which plates enter and are discharged from the pocket 31, said slot being in alignment with said pocket 80 and with a throat or passage 35 provided in the lower end of the frame 29. Suitably mounted within the box 33 and disposed in fixed encircling relation to the slot 34 is a trough-like member 36. Pivotaly mounted 85 to swing into and out of seating relation to said member 36 is a shutter 37 which is normally maintained, as by one or more suitably arranged springs 38, in seated overlying relation to said member 36 for excluding 90 from the pocket 31 light which enters through the slot 34.

The lower end of a plate introduced into the pocket 31 of the plate holder is supported by a hook 39 which normally lies 95 projected into the throat 35 at the lower end of said pocket. Said hook is fixed upon a rock-shaft 40 which extends horizontally through and has rotary movement in the lower end of the frame 29 and which 100 carries on its outer end a small lever 41 whereby it may be moved for swinging said hook into and out of said throat. A spring 42 mounted on or in the back 30 of the plate holder is arranged to bear upon said hook in 105 such manner that chance displacement of the latter from either of its limits of movement is prevented.

The upper end of a plate seated in the pocket 31 is yieldingly engaged by a horizontally disposed vertically movable strip 43 which is of hook-shape in cross-section, as shown in Fig. 9, said strip being slidably held in a groove or channel 44 provided therefor in the upper inner portion of the 110 frame 29 and being depressed by a suitably arranged spring or springs, as 45.

As is obvious, the hook 39 must be swung downward and rearward to an out-of-the-way position with respect to the throat 120 preparatory to entering and discharging plates through the latter; and, also, the shutter 37 must be swung out of closing relation to the slot 34. The movement of the hook 39 is accomplished by means of 125 the lever 41, as has already been explained. The movement of the shutter 37 is accomplished in a manner which will hereinafter be explained. Said shutter 37 is fixed upon a shaft 46 which lies laterally with respect 130

to the slot 34 and has its ends journaled in suitable bearings 47 provided within the ends of the box 33, said ends of said shaft being thence projected outward through said box ends. One of the ends of said shaft carries thereon a head 48 having a cross-groove 49 in its outer face adapted, when the lower end of the plate holder is inserted in the open top of the carriage 13, to receive therein a cross-head 50 carried by the inner end of a short shaft 51 which is journaled in the corresponding end of said carriage and in a bracket 52 mounted on the outer face of said end of the carriage. A knob 53 is fixed on the outer end of said shaft 51 whereby the latter may be rotated for effecting a corresponding rotation of the shaft 46 whereby the said shutter 37 is swung out of and into closing relation to slot 34. Said shaft 51 has fixed thereon between the bracket 52 and the adjacent end of the carriage a spur gear 54 and disposed in underlying meshing relation to the latter is a second spur-gear 55 fixed on the end of a shaft 56 which lies laterally with respect to the slot 22 and which is journaled in the opposite ends of said carriage. The shutter 25 is fixed upon said shaft 56, and, consequently, is actuated to move into and out of closing relation to said slot 22 in unison with the closing and opening movements of the shutter 37.

A radially disposed pin 57 is carried by the gear 54, and, when said gear occupies a position wherein the shutters 25 and 37 are disposed in closing relation to the slots 22 and 34, respectively, said pin is disposed in closely underlying relation to a horizontally movable dog 58 which is disposed laterally with respect to said gear and which, in its normal position, thus prevents rotation of said gear and of the shafts 46 and 56. Said dog is slidably mounted in openings provided therefor in the bracket 52 and in the adjacent end of the carriage and has a spring 59 disposed in inwardly pressing relation to its outer end whereby it is caused to normally occupy an inwardly thrust position with its inner end projected into the interior of the carriage, as shown in Fig. 3. The said inner projecting end of said dog is suitably beveled so that it will be moved outward against the tension of its spring 59 when the box 33 formed on the lower end of the plate holder 28 is introduced in said carriage, the pressure of the end portion of said box on the beveled face of said dog acting to automatically move said dog outward to an out-of-the-way position. When occupying said outwardly thrust, or out-of-the-way position, a groove 60 provided in that face of said dog which is next to gear 54 lies in vertical alinement with said pin 57, whereupon said gear may be rotated for opening the shutters

25 and 37, the pin being rotatable upward through said groove 60.

From the foregoing it will be apparent that it is impossible to swing either the shutter 25 or the shutter 37 to slot-uncovering position until the plate holder has been seated in proper position within the top of the carriage. Thus it is impossible either by chance or by mistake to manipulate the shutters to admit light to the plates contained either in the magazine or in said plate holder. Further, when said shutters occupy open position, the plate holder is locked against removal from the carriage, thus guarding against the admission of light either to the plate holder or to the magazine by accidental or unintentional removal of the carriage prior to closing said shutters. The last-mentioned locking means comprises a cam 61 fixed on the end of shaft 46 opposite that on which the head 48 is fixed, said cam being so disposed that a portion thereof protrudes laterally through an opening or slot 62 provided therefor in the adjacent side plate 14 of the carriage when the shutters are open. When said shutters occupy closed position the cam 61 is withdrawn from the slot 62, permitting of unobstructed withdrawal of the plate holder from the carriage.

For maintaining the plate holder 28 in a perfectly upright position on the carriage, a pivoted latch 63 is provided on the side of the latter at a suitable point, the same being designed to have its hook-like bill 64 neatly seat in a recess 65 provided in the lower part of the frame 29 of said plate holder when such upright position is assumed.

Each of the threaded screws 17 upon which the carriage 13 is mounted carries thereon a bevel gear 66 in mesh with a similar gear 67 carried by a shaft 68 which is journaled in suitable bearings 69 carried by one of the side walls 1 of the casing adjacent to the upper end of the latter. Said shaft 68 has one end extending outward beyond an end wall 2 and carries thereon a small gear 70 which is in mesh with a larger gear 71, the latter being rotatably mounted upon a projecting spindle 72 located upon a plate or bracket 73 which is fixed on said end wall 2 and projects laterally outward slightly beyond the plane of the adjacent side wall 1. A small metallic casing 74 of substantially rectangular form secured upon said plate or bracket 73 incloses said gears 70 and 71. Attached to or formed integral with said gear 71 is a neck or stem 75 which extends outward through said casing 74 and carries on its outer end a knob 76 or other suitable device whereby said gear may be rotated by hand.

Pivottally mounted within the casing 74 is a pair of oppositely disposed pawls 77 and 78 adapted to coöperate with the gear 71, but

only one of which can operatively engage said gear at a time. Said pawls have suitable springs, as 79 and 80, associated therewith and normally acting to maintain said pawls in engagement with said gear. Disposed between said pawls and vertically slideable against the inner face of said casing 74 is a bar 81, the same being fixed upon the inner end of a pin 82 which is movable in a vertical slot 83 provided in said casing 74. A metallic strip 84 mounted on the outer end of said pin 82 is vertically slideable on the outer face of said casing and serves as a finger-piece whereby the bar 81 is shifted. When said bar occupies its uppermost position, it holds the pawl 77 out of engagement with the gear 71 and permits the pawl 78 to engage said gear for preventing forward rotation of the latter. When shifted to its lowermost position, said bar disengages said pawl 78 and permits pawl 77 to engage said gear for preventing rearward rotation of the latter.

In practice, when it is desired to fill the magazine with photographic plates, the same are introduced singly in a dark room by means of the individual plate holder 28 which has its lower end seated in the carriage 13. The plates are inserted in said plate holder through the face thereof, the dark plate 32 of which is removed for the purpose. The carriage is first moved to the limit of its rearward movement, wherein the vertically alined slots 20 and 22 are in vertical alinement with the first of the plate-carrying compartments or pockets formed between the strips 4. The shutters 25 and 37 are opened in the manner hereinbefore described and the hook 39 is withdrawn from supporting relation to the plate, allowing the latter to gravitate into said first pocket. With the plate holder received in the carriage and with the shutters open, the carriage is moved forward by steps from one pocket to another until all are filled or until the desired number of plates has been introduced.

For causing the carriage to accurately aline with the various pockets, thus allowing the plates to accurately enter the latter, I have so arranged the gearing constituting the carriage-moving mechanism that a single complete revolution of the turning knob 76 serves to accurately move said carriage the width of one of said pockets. As a means of gaging the turning movement of said knob, preventing the possibility of the latter being turned too far or not far enough, I have provided in association with said knob an automatic stop, or locking mechanism, comprising a spring-pressed latch 85. Said latch is pivotally mounted in a small radial slot or kerf 86 provided in the stem 75 and is normally held yieldingly pressed outward by a suitable spring,

as 87, into a position wherein a portion thereof protrudes beyond the periphery of said stem. When the carriage occupies the alined position described the protruding portion of said latch 85 occupies a position wherein it is seated in a notch 88 formed in the adjacent edge of the finger piece 84. Then, when it is desired to shift the carriage forward to a position over the next pocket, inward finger pressure applied to a projecting head 89 carried by said latch 85 swings the latter on its pivot to a position wherein said notch 88 is disengaged, whereupon the knob 76 may be rotated forward. When said knob has made a complete revolution, said latch again drops into said notch, preventing further chance rotation.

When the finger piece 84 is elevated to its topmost position for permitting rearward shifting movement of the carriage, the notch 88 is shifted out of range of the latch 85, and, consequently, rearward rotation of the knob for returning the carriage to its initial or starting point over the first pocket of the magazine is not interfered with.

An indicator is preferably provided whereby the precise position of the carriage with respect to the pockets of the magazine is visually indicated. Said indicator consists of a circular disk 90 rotatably mounted on the casing at an appropriate point and having a portion of its periphery underlying a portion of the periphery of the gear 71. Said disk is provided with uniformly spaced peripheral notches 91 of appropriate form and corresponding in number to the number of pockets provided in the magazine. The teeth formed between said notches 91 are consecutively numbered, the numbers 92 appearing on the outer surface of the disk adjacent to the periphery of the latter. A cover plate 93 is disposed over said disk and has an opening or window 94 formed therein through which one of said numbers is exposed to view, said number indicating the pocket of the magazine, numbered consecutively from the initial or first pocket of the latter, with which the openings or slots of the carriage are alined. An inwardly directed stud 95 carried on the inner face of the gear 71 at an appropriate point is designed to engage one of the notches 91 of the disk 90 near the end of each revolution of said gear and to rotate said disk the distance between successive teeth of the latter, thus successively exposing the numbers 92 thereof to view. A suitable brake is provided, whereby chance rotation of the disk 90 is prevented and also whereby movement of said disk beyond the point at which it becomes disengaged from the pin 95 of the rotating gear 71 is prevented. Said brake may be of any appropriate character, but consists in the present embodiment of a body member 96 fixed on the pivot pin 97

about which said disk is rotatable and having a plurality of radially disposed inwardly curved arms 98 frictionally engaging the face of said disk, said body member 5 and arms being made of resilient material so that a yielding pressure is exerted by said arms upon said disk.

As is apparent, when it is desired to remove any certain plate from the magazine, 10 the carriage is moved forward or rearward, as may be necessary, until there is exposed through the window 94 of the cover plate 93 the number indicating the position occupied by said plate. The lower end of the 15 individual plate holder 28 is then fitted in the carriage 13 in the manner hereinbefore described. As said end of the plate holder approaches its seat in said carriage, the beveled inner end of the dog 58 is engaged 20 by the lower edge of the adjacent end of the plate holder, and said dog is thereby thrust outward against the tension of its spring 59. The knob 53 is then rotated forward for swinging the shutters 25 and 37 to open 25 position, and the lever 41 is swung outward to withdraw the hook 39 from the throat 35 of said plate holder. Finally, the magazine and said plate holder are together turned bottom end upward, whereupon the desired 30 plate will gravitate into the pocket 31 of said plate holder. With the magazine and plate holder in said position the hook 39 is returned to its original position. Then, before the plate holder can be removed from 35 the carriage, the shutters 25 and 37 must, as has hereinbefore been explained, be returned to their closed positions. This action serves to release the plate holder, which may then be inserted in a camera in precisely the 40 same manner as the ordinary plate holding slides.

From the foregoing it will be seen that I have described my invention with considerable detail, but it will be obvious that many 45 changes or alterations may be made in the form and arrangement of the various parts without departing from the general spirit or scope of the invention as defined in the appended claims.

50 What is claimed is—

1. A plate holding magazine comprising a casing, spaced pockets within said casing, rollers carried by said casing, a flexible curtain movable over one end of said casing and having its ends connected beneath said rollers, said curtain having a slot therein, a carriage disposed in fixed relation to and movable with said curtain, said carriage being adapted to receive an end of a plate 55 holding slide, and normally closed means for preventing the passage of light through said slot.

2. A plate holding magazine comprising a casing, spaced pockets within said casing, 60 rollers carried at the sides of said casing,

a flexible curtain movable over one end of said casing, straps connecting the opposite ends of said curtain and operating under said rollers, said curtain having a slot therein, a carriage disposed in fixed relation 70 to and movable with said curtain, said carriage being adapted to receive an end of a plate holding slide, and having a slot therein in vertical alinement with the slot in the curtain, means normally maintaining the 75 carriage slot closed, and means for moving the slot-closing means to open position.

3. A plate holding magazine comprising a casing, spaced pockets within said casing, a flexible curtain movable over one end of 80 said casing, said curtain having a slot therein, a carriage disposed in fixed relation to and movable with said curtain, said carriage being adapted to receive an end of a plate holding slide, and having a slot therein in 85 vertical alinement with the slot in the curtain, means normally maintaining the carriage slot closed, and means operable only when said slide is received in said carriage whereby the slot-closing means may be 90 moved to open position.

4. A plate holding magazine comprising a casing, spaced pockets within said casing, a flexible curtain movable over one end of 95 said casing, said curtain having a slot therein, a carriage disposed in fixed relation to and movable with said curtain, said carriage being adapted to receive an end of a plate holding slide, and having a slot therein in 100 vertical alinement with the slot in the curtain, means normally maintaining the carriage slot closed, means operable only when said slide is received in said carriage whereby the slot-closing means may be 105 moved to open position, and means preventing the removal of said slide from said carriage prior to closing of said slot-closing means.

5. A plate holding magazine comprising a casing, spaced pockets within said casing, 110 a flexible curtain movable over one end of said casing, said curtain having a slot therein, a carriage disposed in fixed relation to and movable with said curtain, said carriage being adapted to receive an end of a plate 115 holding slide and having a slot therein in vertical alinement with the slot in the curtain, a shutter normally maintaining the carriage slot closed for excluding light from the interior of the casing, and means operable only when said slide is received in said carriage whereby said shutter may be swung 120 to slot-opening position.

6. The combination with a casing having spaced pockets therein for receiving a plurality of photographic plates, of a flexible curtain movable over one end of said casing, said curtain having a slot therein, a carriage disposed in fixed relation to said curtain and movable therewith, said carriage 130

6 having a passage for plates therethrough, means normally maintaining said passage closed, a plate holding slide having one end adapted to seat in said carriage, said end 5 having a passage therein which is in vertical alinement with said carriage passage when said slide is seated in said carriage, means normally maintaining the slide-passage closed, and coöperating means carried by 10 said slide and said carriage whereby the passage-closing means of both may be simultaneously actuated to move to and from closing position.

7. The combination with a casing having 15 spaced pockets therein for receiving a plurality of photographic plates, of a flexible curtain movable over one end of said casing, said curtain having a slot therein, a carriage disposed in fixed relation to said curtain 20 and movable therewith, said carriage having a passage for plates therethrough, means normally maintaining said passage closed, a plate holding slide having one end adapted to seat in said carriage, said end having a 25 passage therein which is in vertical alinement with said carriage passage when said slide is seated in said carriage, means normally maintaining the slide-passage closed, coöperating means carried by said slide and 30 said carriage whereby the passage-closing means of both may be simultaneously actuated to move to and from closing positions, and means preventing dissociation of said slide from said carriage when said passage-closing means occupy open positions.

8. The combination with a casing having spaced pockets therein for receiving a plurality of photographic plates, of a flexible curtain movable over one end of said casing, 40 said curtain having a slot therein, a carriage disposed in fixed relation to said curtain and movable therewith, said carriage having a passage for plates therethrough, means normally maintaining said passage closed, a plate-holding slide having one end adapted to seat in said carriage, said end having a 45 passage therein which is in vertical alinement with said carriage passage when said slide is seated in said carriage, means normally maintaining the slide-passage closed, coöperating means carried by said slide and 50 said carriage whereby the passage-closing means of both may be simultaneously actuated to move to and from closing positions, means preventing dissociation of said slide from said carriage when said passage-closing means occupy open positions, and means preventing actuation of said passage-closing means when said slide is dissociated from 55 said carriage.

9. The combination with a casing having spaced pockets therein for receiving a plurality of photographic plates, of a flexible curtain movable over one end of said casing, 60 said curtain having a slot therein, a

carriage disposed in fixed relation to said curtain and movable therewith, said carriage having a passage for plates therethrough, means normally maintaining said passage closed, a plate-holding slide having one end adapted to seat in said carriage, said end having a passage therein which is in vertical alinement with said carriage passage when said slide is seated in said carriage, means normally maintaining the slide-passage closed, coöperating means carried by 70 said slide and said carriage whereby the passage-closing means of both may be simultaneously actuated to move to and from closing position, and means preventing actuation of said passage closing means when said slide is dissociated from said carriage.

10. The combination with a casing having spaced pockets therein for receiving a plurality of photographic plates, of a carriage 85 movable over one end of said casing, said carriage having a passage for plates therethrough, means normally maintaining said passage closed, a plate holding slide having one end adapted to seat in said carriage, said 90 end having a passage for plates therein which registers with the passage in said carriage, means normally maintaining the slide-passage closed, coöperating means carried by said slide and said carriage whereby the 95 passage-closing means of both may be simultaneously actuated to move to and from closing positions, means preventing dissociation of said slide from said carriage when said passage-closing means occupy open positions, and means for moving said carriage.

11. The combination with a casing having spaced pockets therein for receiving a plurality of photographic plates, of a carriage movable over one end of said casing, said carriage having a passage for plates therethrough, means normally maintaining said passage closed, a plate-holding slide having one end adapted to seat in said carriage, said end having a passage for plates therein which registers with the passage in said carriage, means normally maintaining the slide-passage closed, coöperating means carried by said slide and said carriage whereby the 105 passage-closing means of both may be simultaneously actuated to move to and from closing positions, means preventing dissociation of said slide from said carriage when said passage-closing means occupy open positions, and means for moving said carriage, said carriage-moving means being 110 adapted to advance the carriage by successive uniform steps of a length corresponding to the width of the pockets in the casing.

12. The combination with a casing having 125 spaced pockets therein for receiving a plurality of photographic plates, of a carriage movable over one end of said casing, said carriage having a passage for plates therethrough, means normally maintaining said 130

passage closed, a plate-holding slide having one end adapted to seat in said carriage, said end having a passage for plates therein which registers with the passage in said carriage, means normally maintaining the slide-passage closed, coöperating means carried by said slide and said carriage whereby the passage-closing means of both may be simultaneously actuated to move to and from closing positions, means preventing disso-
ciation of said slide from said carriage when said passage-closing means occupy open po-
sitions, means for moving said carriage, said carriage-moving means being adapted to 10
15 to advance the carriage by successive uni-
form steps of a length corresponding to the width of the pockets in the casing, and means automatically arresting said advance movement as the carriage successively as-
sumes a position wherein its passage is in register-
ing relation with said pockets.

13. The combination with a casing having spaced pockets therein for receiving a plurality of photographic plates, of a carriage 25 movable over one end of said casing, said carriage having a passage for plates therethrough, means normally maintaining said passage closed, a plate-holding slide having one end adapted to seat in said carriage, said 30 end having a passage for plates therein which registers with the passage in said carriage, means normally maintaining the slide-passage closed, coöperating means carried by said slide and said carriage whereby 35 the passage-closing means of both may be simultaneously actuated to move to and from closing positions, means preventing disso-
ciation of said slide from said carriage when said passage-closing means occupy open po-
sitions, means for moving said carriage, said carriage-moving means being adapted to advance the carriage by successive uniform steps of a length corresponding to the width of the pockets in the casing, and means 40 visually indicating the position of said carriage with respect to said pockets.

14. The combination with a casing having spaced pockets therein for receiving a plurality of photographic plates, of a carriage 50 movable over one end of said casing, said carriage having a passage for plates therethrough, means normally maintaining said passage closed, a plate-holding slide having one end adapted to seat in said carriage, said 55 end having a passage for plates therein which registers with the passage in said carriage, means normally maintaining the slide-passage closed, coöperating means carried by said slide and said carriage whereby 60 the passage-closing means of both may be simultaneously actuated to move to and from

closing positions, means preventing disso-
ciation of said slide from said carriage when said passage-closing means occupy open po-
sitions, means for moving said carriage, said 65 carriage-moving means being adapted to ad-
vance the carriage by successive uniform steps of a length corresponding to the width of the pockets in the casing, means auto-
matically arresting said advance movement 70 as the carriage successively assumes a posi-
tion wherein its passage is in registering re-
lation with said pockets, and means visually indicating the pocket with which said car-
riage passage is in register. 75

15. The combination with a casing adapt-
ed for containing a plurality of photo-
graphic plates, a curtain movable over one end of said casing and having a passage for 80 plates therethrough, means normally occu-
pying light-excluding relation to said pas-
sage, a plate-holding slide adapted to seat over said passage, said slide having a pas-
sage for slides therein, mean normally occu-
pying light-excluding relation to said slide-
passage, means operable only when said 85 slide occupies seated position whereby the light-excluding means for both said passages is moved to and from light-excluding posi-
tions, and means preventing removal of said slide from seating position until said light-
excluding means occupy light-excluding po-
sitions. 90

16. The combination with a casing adapt-
ed for containing a plurality of photo-
graphic plates, a curtain movable over one end of said casing and having a passage for 95 plates therethrough, means normally occu-
pying light-excluding relation to said pas-
sage, a plate-holding slide adapted to seat over said passage, said slide having a pas-
sage for plates therein, means normally occu-
pying light-excluding relation to said slide-
passage, means operable only when said 100 slide occupies seated position whereby the light-excluding means for both said pas-
sages is moved to and from light-excluding posi-
tions, means preventing removal of said slide from seating position until said light-
excluding means occupy light-excluding po-
sitions. 105

In testimony whereof, I affix my signa-
ture in presence of two subscribing wit-
nesses.

GEORGE C. BRUHN, Jr.
